CLAMP FOR FUSES, RELAYS, ETC.

Charles E. Hanny, Plainville, Conn., assignor to
The Trumbull Electric Manufacturing Company, Plainville, Conn., a corporation of Connecticut

Application September 24, 1942, Serial No. 459,503

7 Claims. (Cl. 200—134)

This invention relates to clamps for fuses, relays, etc.

An object of the invention is to provide a clamp of this character that is simple and rugged in construction, inexpensive to manufacture and light in weight.

Another object is to provide a clamp of this kind having a movable screw member with means for bracing the clamp against the pressure of the screw.

Another object is to prevent endwise movement of the fuse or the like.

In its simplest form, the clamp consists of three parts, namely, a main support, a hooded seat or abutment and a clamp screw. The support and the screw seat or abutment are formed of sheet metal and suitably secured together by welding or riveting at a single point and interlocked adjacent the clamp screw. Two forms are shown herein to accommodate respectively a fuse or relay having a cylindrical or ferrule type terminal and one having a flat blade type terminal.

Fig. 1 is a perspective view showing a pair of fuse clamps mounted for holding a cartridge type fuse or relay with ferrule type ends or terminals.

Fig. 2 is an end view of one of the clamps, part being broken away and parts being shown in section.

Fig. 3 is an edge view of the clamp of Figs. 1 and 2.

Fig. 4 is a sectional view of the same on the plane of the line 4—4 of Fig. 2.

Fig. 5 is an end view of a type of clamp for holding a blade type terminal.

Fig. 6 is a detail view of the main support of Fig. 5.

Fig. 7 is an edge view of the clamp of Figures 5 and 6.

The main support 9 has a foot 10 by which it may be secured to a suitable base. This support has a seat 11 on which rests the terminal of the fuse or relay.

The seat 12 for the clamp screw 13 is in the form of a hood of U-shaped section and has flanges 14 which embrace the upright of the support 9 and are welded or riveted to it at 15. The seat 12 also has a notch 16 adjacent the screw into which the tip 17 of the support 9 fits so that the thrust of the screw against the fuse terminal will be resisted by the engagement of the shoulder 18 of the hood against the tip 17 of the support as well as by the connection 15. The outer wall 19 of the hood serves as a stop

to limit the longitudinal movement of the fuse or the like.

In the form of Figs. 5 to 7, the support 20 has a seat 21 for the fuse blade 21'. The clamp seat 22 for screw 23 is similar to that of Figs. 1 to 4 and is riveted or welded at 24 to the support and interlocked with it at 25.

In both forms, it will be seen that the clamp screw seat member is of channel-like section so as to afford a maximum strength for a minimum amount of metal. There is also a rigid connection between the support and the clamp seat produced by the interlock at the top and the single rivet or weld at the bottom.

In both forms, portions of the screw seat act as stops to limit endwise movement of a fuse inserted in a pair of the clamps. In the form shown in Figs. 1 to 4, this stop is on an inside surface of the seat member but near the outer edges of each pair of clamps. In the form shown in Figs. 5 to 7, the stop is simply the outside surface of the seat member between each pair of clamps.

From the foregoing it will be seen that my improved fuse clamp is simple, light in weight, rugged and compact, and inexpensive to manufacture; that it permits easy insertion and removal of the fuses and insures a full contact under pressure and proper alignment of fuse terminals.

I claim:

1. A fuse clamp comprising a flat sheet metal support having a seat for the terminal of a fuse and a sheet metal U-shaped hood member extending over said seat, parts of said hood member being secured to said support adjacent said seat, a clamp screw in the hood member to engage a fuse terminal supported in said seat and another part of said hood member having means interlocked with said support adjacent said screw.

2. A fuse clamp comprising a support having a seat portion for a fuse, a substantially U-shaped hood member straddling said support and having a screw-threaded opening for a clamping screw, means of connection between said support and hood member adjacent said seat portion and means of connection between said support and hood member adjacent said screw-threaded opening for resisting the pressure of the clamping screw.

3. A fuse clamp comprising a support having an upright portion and a seat portion for supporting the end of a fuse, a substantially U-shaped hood member, the walls of said hood member straddling said upright portion and se-

cured thereto adjacent the seat portion, the cross piece of said hood member having a screw-threaded opening for receiving a clamping screw and a slot and stud connection between said upright portion of the support and said cross piece of the hood member adjacent said screw-threaded opening for resisting the pressure of the clamping screw.

4. A fuse clamp comprising a support having an upright portion and a seat for supporting the end of a fuse, a substantially U-shaped hood member forming a seat for a clamping screw, the spaced walls of said hood member straddling said upright and one wall thereof extending beyond the edge of said upright portion to form a stop for preventing endwise movement of the fuse.

5. A fuse clamp comprising a support having an upright portion and an arcuate seat portion for a fuse, a substantially U-shaped hood member having a portion straddling said upright and having a cross-piece above the seat with a clamping screw for engagement with a fuse, means of connection between said support and hood member adjacent said seat portion and means of con-

nection between said support and hood member adjacent said seat portion for resisting the pressure of the clamping screw.

6. A fuse clamp comprising a support having a base and an upright, said upright having a fuse seat, a hood having side arms rigidly secured to the support adjacent the base and a cross-piece connecting the side arms and interlocked with the upright, a clamp screw adjustable in said cross-piece toward and from the fuse seat, said cross-piece and upright having cooperating parts to resist the backward thrust of the clamp screw against a fuse supported in said seat.

7. A fuse clamp comprising a support having an upright with a fuse seat, a hood straddling the upright and secured to the support, said upright and hood having interlocking parts to prevent rotation of the hood on the support, said hood having a wall extending parallel with the upright opposite the fuse seat to serve as a stop for the end of a fuse supported in said seat and a clamp screw adjustable in said hood toward and from said fuse seat.

CHARLES E. HANNY.
